UNITED STATES PATENT OFFICE

JOHN W. THOMAS, OF KANSAS CITY, KANSAS.

COMBINED RAIL-ANCHOR AND TIE-PLATE.

1,137,810.

Specification of Letters Patent.

Patented May 4, 1915.

Application filed September 21, 1914. Serial No. 862,713.

To all whom it may concern:

Be it known that I, JOHN W. THOMAS, a citizen of the United States, residing at Kansas City, in the county of Wyandotte and State of Kansas, have invented certain new and useful Improvements in Combined Rail-Anchors and Tie-Plates, of which the following is a specification.

My invention relates to improvements in combined rail anchors and tie plates, and the objects of the invention are first, to prevent railroad rails from becoming embedded in the ties, second, to prevent the rails from creeping longitudinally, third, to prevent the rails from tipping sidewise when subjected to lateral pressure, such as is exerted by car wheel flanges when rounding a curve in a track, and fourth, to prevent the spikes which assist in holding the rails upon the device from becoming accidentally withdrawn from the underlying ties.

In order that the invention may be fully understood, reference will now be made to the accompanying drawing, in which:

25 Figure 1 is a cross section of a rail in position upon one of the devices. Fig. 2 is a plan view of one of the devices. Fig. 3 is a broken vertical section, enlarged, on line III—III of Fig. 2. Fig. 4 is an end view of the device.

30 A designates a rail of the usual construction embodying a ball B, a base C, and a web D uniting said ball and the base.

The device constituting the present invention consists of a plate 1 provided near one side with an abutment 2 and near its opposite side with an overhanging flange 3. The abutment 2 and the overhanging flange 3 are spaced apart to abut the opposite sides of 40 the rail base C as disclosed by Fig. 1. The upper edge 4 of the abutment 2 slopes toward the rail base C, for a purpose which will hereinafter appear. Said abutment 2 is interrupted by spike holes 5 to receive spikes 45 E, which are driven into the underlying tie F.

50 6 designates shoulders extending upwardly from certain margins of the spike holes 5, to abut the heel of the spikes E as disclosed by Fig. 1. Shoulders 6 are reinforced with ribs 7 extending down to the plate 1.

55 The overhanging flange 3 extends the full length of the plate 1 and has a threaded opening 8 at its central portion, where it is reinforced with a rib 9. Spike holes 10 are

provided in the plate 1 adjacent the base of the flange 3, to receive spikes G, which, like the spikes E, are driven into the underlying tie F.

60 11 designates a set-screw engaging the internal threads of the opening 8 and adapted to bear upon the underlying portion of the rail base C, as disclosed by Fig. 1.

65 In practice, the plate 1 is secured to the underlying tie F with the spikes G, the heels g of which bear against the adjacent side of the overhanging flange 3 with sufficient friction to prevent said spikes G from accidentally pulling upward out of the tie, 70 which is a common occurrence where no means are provided for holding the spikes down in the tie. The rail is then placed upon the tie with one side of its base raised upon the bevel surface 4 and the opposite side of said 75 base beneath the overhanging flange 3, under which it is finally forced home by applying sufficient pressure upon the rail to cause it to slip off the bevel surface 4 and become flatly seated upon the plate 1. The 80 side of the rail base C bearing against the abutment 2 is then firmly secured in place with the spikes E, which are reliably held from working up and out of the tie by the upper ends of the shoulders 6, which are 85 bent over the heels e of said spikes E, as disclosed by Fig. 1. The opposite side of the base is prevented from tipping upward by the overhanging flange 3, and the rail is prevented from creeping longitudinally by the 90 spikes E and the set-screw 11, which latter is screwed down firmly into engagement with the underlying rail base.

Having thus described my invention, what I claim and desire to secure by Letters Patent, is:

1. In a device of the character described, a plate, an abutment on said plate adjacent one side thereof and provided with a bevel upper surface, an overhanging flange on 100 said plate near one margin thereof provided with a threaded opening, and a set-screw engaging the threads of said opening.

2. In a device of the character described, a plate, an abutment on said plate near one 105 margin thereof, an overhanging flange on said plate near an opposite margin thereof and provided with a threaded opening, a reinforcement for said overhanging flange surrounding the threaded opening therein, and 110 a set-screw for engaging the threads of said opening.

3. In a device of the character described, a plate having spike holes therein, shoulders adjacent certain margins of said spike holes and adapted to be bent over the heels of 5 spikes driven through the spike holes, an abutment on the plate adjacent one margin thereof and interrupted by a number of the spike holes, an overhanging flange on the plate near an opposite margin thereof, said 10 overhanging flange having a threaded open-

ing extending therethrough, and a set-screw adapted to engage the threads of said opening.

In testimony whereof I affix my signature, in the presence of two witnesses.

JOHN W. THOMAS.
